US0D1076067S

(12) **United States Design Patent** (10) **Patent No.:** **US D1,076,067 S**
(45) **Date of Patent:** **** May 20, 2025**

(54) **SYRINGE**

(71) Applicant: **Susan Reynolds**, St. Paul, MN (US)

(72) Inventor: **Susan Reynolds**, St. Paul, MN (US)

(73) Assignee: **Susan Reynolds**, St. Paul, MN (US)

(**) Term: **15 Years**

(21) Appl. No.: **29/826,777**

(22) Filed: **Feb. 15, 2022**

Related U.S. Application Data

(63) Continuation of application No. 29/733,079, filed on Apr. 29, 2020, now Pat. No. Des. 957,625.

(57) **CLAIM**

The ornamental design for a syringe as shown and described.

DESCRIPTION

FIG. 1 is a top perspective view of a syringe; FIG. 2 is a bottom perspective view of the syringe of FIG. 1;

FIG. 3 is a front side view of the syringe of FIG. 1, the rear side view, the left side view, and the right side view being a mirror image thereof;

FIG. 4 is a top side view of the syringe of FIG. 1;

FIG. 5 is a bottom side view of the syringe of FIG. 1;

FIG. 6 is a cross-section view taken at line **6-6** of FIG. 3, illustrating the shape and contour of the syringe of FIG. 1;

FIG. 7 is top perspective view of a second syringe;

FIG. 8 is bottom perspective view of the syringe of FIG. 7;

FIG. 9 is a front side view of the syringe of FIG. 7;

FIG. 10 is a left side view of the syringe of FIG. 7, the right side view being a mirror image thereof;

FIG. 11 is a rear side view of the syringe of FIG. 7;

FIG. 12 is a top side view of the syringe of FIG. 7;

FIG. 13 is a bottom side view of the syringe of FIG. 7; and, FIG. 14 is a cross-section view taken at line **14-14** of FIG. 12, illustrating the shape and contour of the syringe of FIG. 7.

The broken lines in the figures depict portions of the syringe that form no part of the claimed design.

1 Claim, 10 Drawing Sheets
